PYROPHORIC LIGHTER

Percy Searle Richards, London, England, assignor
to The Parker Pipe Company Limited, London,
England

Application December 22, 1941, Serial No. 424,082
In Great Britain December 31, 1940

6 Claims. (Cl. 67—7.1)

This invention relates to pyrophoric lighters of the kind wherein the opening of the lighter is adapted to operate the ignition mechanism automatically and has for its object to provide an improved form of operating mechanism for a lighter of this type.

According to the present invention the lighter is provided with a cover carried by an arm which is pivoted in the lighter casing and connected by a link with a rotary abrasive wheel, the arm being adapted to be actuated by a pivoted lever which is connected therewith to form a toggle joint the pivoted point of which is engaged by a snap over spring, the arrangement being such that upon the lever being turned about its pivot to bring the members of the joint past the dead centre position, the snap over spring effects the rapid lifting of the wick cover and simultaneously therewith a rapid actuation of the link to rotate the abrasive wheel. A finger operated sliding member may be provided for actuating the lever.

To enable the invention to be fully understood it will now be described with reference to the accompanying drawing which is a sectional view of the upper part of a lighter casing shewing actuating mechanism constructed according to one embodiment of the invention.

As shewn in the drawing the lighter casing 1 comprises a fuel container 2, and is provided with a wick 3, flint 4 and rotary abrasive wheel 5. A wick cover or extinguisher 6 is formed integrally with an arm 7 pivoted in the lighter casing at 3. An actuating link 9 is provided one end being pivoted at 10 to a one-way clutch member 11 of known type arranged adjacent to the wheel 5. The other end of the link 9 is formed with a slot 12 which is engaged by a pivot pin 13 on the end of the arm 7. The arm 7 is pivotally connected with a lever 14 whose opposite end is slidably mounted in a crank member 15 which is pivotally mounted at 16 in the lighter casing. The lever 14 and arm 7 form a toggle joint and a coil spring 16 is fitted over the lever 14 with its ends respectively abutting the pivoted point of the toggle joint and the crank member 15 so as to effect a snap over action of the members of the joint when they have been moved past dead centre position.

A portion 17 of the crank member projects substantially at right angles to the lever 14 and abuts against a pusher member 18 which is slidably arranged in the lighter casing with a portion 19 projecting from the side of the casing to form a push button.

In operation the button 19 is pushed inwardly by the finger of the operator and as it slides it engages the projection 17 and rotates the crank member about its pivot. The lever 14 is carried round with the crank member and it initiates the rotation of the arm 7 until the toggle joint formed by the arm 7 and the lever 14 passes its dead centre position. At this position the spring 16, which is normally under compression, becomes operative to effect a rapid rotation of the arm 7 to lift the wick cover. Simultaneously with the lifting of the wick cover the link 9 is rapidly actuated by the pin 13, and the clutch 11 and the abrasive wheel 5 coupled thereto are rotated over the flint 4 to ignite the wick 3.

When the wick cover is closed, the parts are moved back into the original position and the lever 14 and the adjacent end of the arm 7 form a substantially straight line as shewn in the drawing.

The mechanism may be so designed that the arm 7 and wick cover form part of the top cover of the lighter casing so that a flush closure is provided.

The one-way clutch coupling may consist of a disc slidably mounted on the spindle of the abrasive wheel and having ratchet teeth thereon adapted to engage recesses or projections on the side of the wheel, a spring being provided for pressing the disc into contact with the wheel.

The described mechanism may be mounted as a self-contained unit which can be fitted into the end of a lighter casing and detachably secured thereto.

I claim:

1. In a pyrophoric lighter, a casing, an arm pivoted to the casing and carrying a wick cover, a rotary abrasive wheel mounted on the casing, a link connecting the wheel with the arm, a pivoted lever for actuating the arm and connected therewith to form a toggle joint and a snap-over spring operatively connected with the pivotal point of the toggle joint to effect the rapid rotation of the arm about its pivot and the simultaneous rotation of the abrasive wheel when the toggle joint has been moved past the dead centre position.

2. In a pyrophoric lighter, a casing, an arm pivoted to the casing and carrying a wick cover, a rotary abrasive wheel mounted on the casing, a link connecting the wheel with the arm, a pivoted lever for actuating the arm and connected therewith to form a toggle joint, a manually operable slide for rotating the lever past its dead

centre position and a snap-over spring operatively connected with the pivotal point of the toggle joint to effect the rapid rotation of the arm about its pivot and the simultaneous rotation of the abrasive wheel when the toggle joint has been moved past the dead centre position.

3. In a pyrophoric lighter, a casing, an arm pivoted to the casing and carrying a wick cover, a rotary abrasive wheel mounted on the casing, a link connecting the wheel with the arm, a pivoted lever for actuating the arm and connected therewith to form a toggle joint, a crank member pivoted to the casing and forming a bearing in which the free end of the lever is slidably mounted, means for rotating the crank member and a snap-over spring operatively connected with the pivotal point of the toggle joint to effect the rapid rotation of the arm about its pivot and the simultaneous rotation of the abrasive wheel when the toggle joint has been moved past the dead centre position.

4. In a pyrophoric lighter, a casing, an arm pivoted to the casing and carrying a wick cover, a rotary abrasive wheel mounted on the casing, a link connecting the wheel with the arm, a pivoted lever for actuating the arm and connected therewith to form a toggle joint, a crank pivoted to the casing and forming a bearing in which the free end of the lever is slidably mounted, a manually operable slide for rotating the crank member, and a snap-over spring operatively connected with the pivotal point of the toggle joint to effect the rapid rotation of the arm about its

5 pivot and the simultaneous rotation of the abrasive wheel when the toggle joint has been moved past the dead centre position.

5. In a pyrophoric lighter, a casing, an arm pivoted to the casing and carrying a wick cover, a rotary abrasive wheel mounted on the casing, a link connecting the wheel with the arm, a pivoted lever for actuating the arm and connected therewith to form a toggle joint, a crank member pivoted to the casing and forming a bearing in which the free end of the lever is slidably mounted, means for rotating the crank member and a snap-over coil spring surrounding the lever with its ends respectively abutting the crank member and the pivotal point of the toggle joint to effect the rapid rotation of the arm about its pivot and the simultaneous rotation of the abrasive wheel when the toggle joint has been moved past its dead centre position.

6. In a pyrophoric lighter, a casing, an arm pivoted to the casing and carrying a wick cover, a rotary abrasive wheel mounted on the casing, a link connecting the wheel with the arm and having a pin and slot connection with the arm, a pivoted lever for actuating the arm and connected therewith to form a toggle joint and a snap-over spring operatively connected with the pivotal point of the toggle joint to effect the rapid rotation of the arm about its pivot and the simultaneous rotation of the abrasive wheel when the toggle joint has been moved past the dead centre position.

PERCY SEARLE RICHARDS.
